Primary Examiner — Austin Murphy(74) *Attorney, Agent, or Firm* — Seager, Tufte & Wickhem LLP(57) **CLAIM**

The ornamental design for a front panel for a video recorder, as shown and described.

DESCRIPTION

FIG. 1 is a first perspective view of the front panel for a video recorder;

FIG. 2 is a second perspective view thereof;

FIG. 3 is a front elevation view thereof;

FIG. 4 is a right side elevation view of the front panel for a video recorder, the opposing side view being a mirror image thereof;

FIG. 5 is a top plan view thereof; and,

FIG. 6 is a bottom plan view thereof.

The broken lines in the drawings depict subject matter that is hereby disclaimed and forms no part of the claimed design. The rear view of the front panel for a video recorder illustrated in FIGS. 1–6 is hereby disclaimed and forms no part of the claimed design.

1 Claim, 4 Drawing Sheets
